UNITED STATES PATENT OFFICE.

HANS HARTMAN, OF LONDON, ENGLAND, ASSIGNOR TO DUPLEX VENDING MACHINE COMPANY INC., OF NEW YORK, N. Y., A CORPORATION OF NEW YORK.

DESIGN FOR A CASING FOR VENDING-MACHINES.

49,611.

Specification for Design.

Patented Sept. 5, 1916.

Application filed November 28, 1914. Serial No. 874,547. Term of patent 3½ years.

To all whom it may concern:

Be it known that I, HANS HARTMAN, a subject of the Emperor of Austria-Hungary, residing in the city of London, England, have invented a new, original, and ornamental Design for a Casing for Vending-Machines, of which the following is a specification, reference being had to the accompanying drawing, forming part hereof.

Figure 1 is a front elevation of a casing

for vending machines showing my new design. Fig. 2 is a side elevation of the same; and Fig. 3 is a plan view of the same.

I claim:

The ornamental design for a casing for vending machines, as shown.

HANS HARTMAN.
